UNITED STATES PATENT OFFICE.

EDWARD A. RUSSELL, OF CHICAGO, ILLINOIS, ASSIGNEE TO VAPOR CAR HEATING COMPANY, INC., OF CHICAGO, ILLINOIS, A CORPORATION OF NEW YORK.

CONTROLLING MECHANISM FOR HEATING SYSTEMS.

Application filed June 16, 1919. Serial No. 304,442.

To all whom it may concern:

Be it known that I, EDWARD A. RUSSELL, a citizen of the United States, residing at Chicago, in the county of Cook and State 5 of Illinois, have invented certain new and useful Improvements in Controlling Mechanism for Heating Systems, of which the following is a specification.

My invention relates to mechanism for controlling the flow of fluids through a circulatory system, and particularly to a controlling mechanism for a steam heating system intended for heating railway cars; and the principal object of the invention is to 15 provide a new and improved controlling valve for the radiator of a heating system and mechanism for opening and closing said valve automatically, in response, for example, to fluctuations in the temperature of 20 the car atmosphere.

The invention consists in the new and improved constructions, arrangements and devices to be hereinafter described and claimed for carrying out the above stated 25 object and such other incidental objects as will appear from the following description of the preferred embodiment illustrated in the accompanying drawings.

In the drawings,

30 Fig. 1 is a diagram in perspective of the car heating system provided with the controlling means which is the subject matter of this invention.

Fig. 2 is a view, in perspective, of the 35 valve member by the movement of which the control of circulation of heating medium through the radiator is obtained.

Fig. 3 is a view, in elevation, of the controlling device, the valve and its motor.

40 Fig. 4 is a detail view, partly in section and partly in elevation, of the valve member shown in Fig. 2 and the fluid motor piston by which movement in one direction is imparted to the valve.

45 Fig. 5 is a vertical sectional view of the controlling mechanism including the thermostatically actuated motor, for governing

the application of pressure fluid to the valve piston, and

Fig. 6 is a horizontal section taken substantially on the line 6—6 of Fig. 5. 50

Fig. 7 is a horizontal section taken substantially on the line 7—7 of Fig. 5, showing the valve assembly in a different position of adjustment. 55

Fig. 8 is a horizontal section taken substantially on line 8—8 of Fig. 5.

Like characters of reference designate like parts in the several figures of the drawings.

Referring first to Fig. 1, A is a radiating coil arranged within the car, the floor of which latter is indicated at B. C is the steam train pipe (the invention having to do particularly with a steam heating system). D is a vapor regulator of common 60 construction which operates to control the inflow of steam from the train pipe C to the radiator A in accordance with the temperature of the medium outflowing from the radiator so as to maintain the medium 65 in the radiator at substantially atmospheric pressure. E is a four-way valve which in one position of its valve member directs low pressure steam from the vapor regulator to the radiator and directs outflow of 70

medium from the radiator to the thermostat chamber of the vapor regulator, and in another position of said valve member shuts off both ends of the radiator, putting them in communication with a drainage port, and 75 directs the low pressure steam from the vapor regulator through a circuit which leads back to the thermostat chamber of said vapor regulator so that the regulator, which is exposed to the weather, will be kept from freezing. 80

F is a fluid pressure motor for operating the four-way valve. G is a thermostat located in the car so as to be subject to fluctuations in the temperature of the car atmosphere, and H is an electric 85 motor in circuit with the thermostat and source of supply of electric current I for governing the application of pressure fluid to the motor F. 90

The four-way valve E comprises a casing 10 having interior webs 11, 12, 13, 14, dividing it into four chambers 15, 16, 17 and 18. A pipe consisting of sections 19 and 20 between which the vapor regulator D is interposed leads from the train pipe C to chamber 15, pipes C, 19 and 20 constituting what might be termed the supply pipe for radiator A. The inflow pipe 21 is connected with casing 10 so as to lead from chamber 16. The outflow pipe 22 of the radiator leads to chamber 17. 23 is a pipe leading from chamber 18 to the thermostat chamber of the vapor regulator. Further description of the vapor regulator will be unnecessary as this device is in common use and is described in a number of patents on car heating apparatuses granted to Egbert H. Gold, for example, Patent No. 987,570 dated March 21, 1911. In the space 24 between chambers 15, 16, 17, 18 of the four-way valve is arranged a bushing 25 having openings corresponding to the openings between the chambers and space 24. The bushing and web 13 are pierced with drainage ports 26 leading to a drain pipe 27. Within the bushing is a valve member 28 (Figs. 2 and 4) which is movable in the direction of its length and is also revoluble. This device comprises three discs 29, 30 and 31, connected by vertical webs 32 and 33 which stand at right angles to each other. The upper disc 29 is formed with a boss 34 to which is secured loosely by pin 35 a stem 36 in the upper end of which is fixed a laterally extending guide pin 37, the ends of which project into guide slots 38 in a hollow cylindrical member 39 arranged within a bonnet 40 secured to the top of casing 10, the hollow cylindrical member being formed with a threaded stud 41 engaged by a nut 42 and with a head 43 adapted to bear against a packing 44 in the upper end of bonnet 40. The lower end of the valve member 28 is enclosed by a thimble 45 threaded into a boss 46 on the bottom of casing 10, the thimble being formed with a flange 47 which clamps an annular member 48 against the under side of casing 10. The valve member 28 is moved upwardly by fluid pressure exerted against a piston 49 having a stem 50 bearing against the under side of the disc 31 of the valve member, the stem 50 being provided with a portion 51 of reduced diameter which projects into an opening 52 extending through disc 31 and into web 33. The valve is moved in the other direction by means of a coiled spring 53 interposed between the head 43 of cylindrical member 39 and the upper disc 29 of the valve member 28. A casting 54 is secured by bolts 55 to the annular member 48 bearing against the lower web 56 of the thimble 45. This casting 55 has a cylindrical bore provided with a cy-

lindrical bushing 57 within which piston 49 slides, its stem 50 extending through an opening 59 in web 56. The latter is provided with ports 60 to permit outflow of air from cylinder 57 when the piston 49 is raised. In the lower part of casting 54 is an opening 61 providing a valve chamber for a valve to control the admission of fluid pressure to cylinder 57 under piston 49. In the embodiment of the invention shown the pressure fluid applied to piston 49 is taken from the train pipe C through a pipe 62 which is threaded into the side of casting 54 in line with the valve chamber 61. Arranged in the inner end of the valve chamber is a valve seat 63 provided with a relatively small port 64 putting the valve chamber in communication with pipe 62. This seat is held in place by a bushing 65 screwed into the casting 54, the outer end of the bushing (see Fig. 7) being formed with a valve seat 66. The controlling element for the fluid pressure consists of a valve 67 to cooperate with seat 66 and a valve 68 having a threaded engagement with valve 67 for adjustment to cooperate with the valve seat 66. A coiled spring 69 is interposed between lugs 70 on valve 67 and the valve seat member 63. An exhaust fitting 71 is fixed in the end of bushing 65. Valve 67 is provided with a stem 72 which extends through the exhaust fitting 71 and is engaged by an adjustable stud 73 on the end of a bell crank lever 74 pivoted at 75 to a web 76 forming part of casting 54. A lock nut 77 holds stud 73 at the proper adjustment. The long arm of the bell crank lever 74 is engaged by a rod 78 to the upper end of which is secured the armature 79 of an electro-magnet 80, the magnet and the armature constituting what has been termed the motor H and being enclosed in a casing 81 supported on a piece of tubing 82 fixed to a boss 83 formed on the web 76 of casting 54. 84, 85 are wires leading from the coil of magnet 80 to one member of the thermostat G and the other to the battery I. 86 (Fig. 1) is the wire from the battery to the other member of the thermostat. The bell crank lever is preferably enclosed by a shield plate 87. The valve member of four-way valve E is also operable by hand for emergency purposes. With this in view the valve member is made revoluble as well as movable in the direction of its length. The stud 41 of the hollow cylindrical member 39 is provided with a squared portion 88 to which a handle 89 is fixed by means of a nut 90 on the threaded upper end 91 of the stud. This handle is slightly resilient and terminates in a forked portion 92 normally engaged with a stud 93 on the casing 10. The handle may be bent slightly to free it from the stud and moved a quarter of a turn into engage-

ment with a stud 94. This will shift the valve member 28, whether the latter be in its upper or in its lower position, so as to reverse the position either of web 32 or web 33, as the case may be.

Operation: The thermostat G, the particular construction of which does not concern this invention, is shown in a simplified and diagrammatic way. It will be assumed that 10 it operates by rise of temperature to close the circuit through magnet H. Fig. 5 of the drawings shows the parts of the apparatus in the positions which they take with the magnet energized and valve 68 closing the 15 port 64 through which fluid pressure is admitted to the cylinder 57. With no pressure on the under side of the cylinder, valve 67 standing open, spring 53 will maintain the valve member 28 in its lower position so that 20 its upper web 32 will be in position in the casing 10 of the four-way valve standing across the space 24 in line with webs 12 and 14 (Fig. 6). Steam entering chamber 15 of the four-way valve E from pipes C, 19 and 25 20 (its pressure being reduced by vapor regulator D) will pass into chamber 18 and out through pipe 23 to the thermostat chamber of the vapor regulator in sufficient amount to keep the vapor regulator from 30 freezing. The operation of the vapor regulator prevents any waste of steam. If the radiator A contains any water of condensation it may escape from both pipes 21 and 22 to the discharge pipe 27 through the port 35 26. As soon as the temperature of the atmosphere falls below the point for which thermostat G is set the thermostat operates to break the circuit through magnet H and spring 69 moves valve 67 against its seat 40 66 and at the same time moves valve 68 to open port 64, as is shown in Fig. 7. Steam pressure from pipe 62 enters valve chamber 61 and is exerted against the under side of piston 49 raising the piston and with it the 45 valve member 28 so as to bring the lower web 33 thereof into the space 24 in four-way valve E. The web 33 being at right angles to the web 32 will take the position shown in the dotted lines in Fig. 6, closing the 50 outlet port 26 and putting the supply pipe 20 in communication with the inflow end 21 of the radiator A and putting the outflow end 22 of radiator A in communication with the discharge pipe 23. Steam is now circulated 55 through the radiator A, the waste of steam being prevented by the operation of the vapor regulator. In either of the upper or lower positions of the valve member the control may be reversed in case of emergency 60 by rotating the valve member a quarter of a turn by means of handle 89.

It will be obvious that changes in the form and construction of the parts of the apparatus as shown and described may be made 65 without departure from the principles of the

invention. Certain common elements of the heating system have been shown in a simplified and diagrammatic manner. I have shown a two-pipe radiating coil but it will be obvious that the invention is applicable, 70 with certain obvious modifications, to a two-coil system. The word "pipe," as used in the claims is not employed in a limiting sense. I intend thereby any conduit forming means.

I claim:

1. In a heating system, the combination of a supply pipe, a radiator having inflow and outflow pipes, a discharge pipe, and a controlling device comprising a casing 80 having ports communicating with said pipes, and a valve member movable longitudinally through said casing which in one position puts the supply pipe in communication with the inflow pipe and the outflow pipe in communication with the discharge pipe and in another position shuts off the inflow and outflow pipes and puts the supply pipe in direct communication with the discharge pipe.

2. In a heating system, the combination of a supply pipe, a radiator having inflow and outflow pipes, a discharge pipe, and a controlling device comprising a casing 95 having ports communicating with said pipes, and a drain port, and a valve member movable longitudinally through said casing which in one position puts the supply pipe in communication with the inflow pipe and the outflow pipe in communication with the discharge pipe and closes the drain port, and in another position shuts off the inflow and outflow pipes, opens the drain port and puts the supply pipe in direct communication with the discharge pipe.

3. In a heating system, the combination of a supply pipe, a radiator having inflow and outflow pipes, a discharge pipe, and a controlling device comprising a casing 100 having ports communicating with said pipes, and a valve member movable longitudinally through said casing and formed with two longitudinally extending webs arranged successively lengthwise of the member and standing at an angle with respect to each other, one of which webs is arranged so as to put the supply pipe in communication with the inflow pipe and the outflow pipe in communication with the discharge pipe and the other of which is arranged to shut off the inflow and outflow pipes and put the supply pipe in direct communication with the discharge pipe.

4. In a heating system, the combination of a supply pipe, a radiator having inflow and outflow pipes, a discharge pipe, and a controlling device comprising a casing having ports communicating with said pipes, and a valve member movable longitudinally through said casing which valve member in

one position puts the supply pipe in communication with the inflow pipe and the outflow pipe in communication with the discharge pipe and in an alternative position 5 shuts off the inflow and outflow pipes and puts the supply pipe in direct communication with the discharge pipe, said valve member being revoluble so as to effect the alternative connections above specified by 10 angular movement as well as by longitudinal movement.

5. In a heating system, the combination of a supply pipe, a radiator having inflow and outflow pipes, a discharge pipe, and a 15 controlling device comprising a casing having ports communicating with said pipes, and a drain port, and a valve member movable longitudinally through said casing which valve member in one position puts 20 the supply pipe in communication with the inflow pipe and the outflow pipe in communication with the discharge pipe and closes the drain port, and in an alternative position shuts off the inflow and outflow pipes, opens 25 the drain port and puts the supply pipe in direct communication with the discharge pipe, said valve member being revoluble, so as to effect the alternative connections above specified by angular movement as well as by 30 longitudinal movement.

6. In a heating system, the combination of a supply pipe, a radiator having inflow and outflow pipes, a discharge pipe, and a controlling device comprising a casing having 35 ports communicating with said pipes, and a valve member movable longitudinally through said casing and also mounted revolubly therein and formed with two longitudinally extending webs arranged successively lengthwise of the member and standing at an angle with respect to each other, one of which webs is arranged so as, in one longitudinal position of the valve member, to put the supply pipe in communication with the inflow pipe and the outflow pipe in communication with the discharge pipe, and the other of which webs is arranged so as in another longitudinal position of said valve member, to shut off the 45 inflow and outflow pipes and put the supply pipe in direct communication with the discharge pipe.

7. In a heating system, the combination of a supply pipe, a radiator having inflow and outflow pipes, a discharge pipe, a controlling device comprising a casing having ports communicating with said pipes, and a valve member movable longitudinally through said casing which valve member in 50 one position puts the supply pipe in communication with the inflow pipe and the outflow pipe in communication with the discharge pipe and in another position shuts off the inflow and outflow pipes and puts 55 the supply pipe in direct communication

with the discharge pipe, a piston connected with said valve member, and a cylinder in which said piston operates adapted to receive a pressure fluid.

8. In a heating system, the combination 70 of a supply pipe, a radiator having inflow and outflow pipes, a discharge pipe, a controlling device comprising a casing having ports communicating with said pipes, a valve member movable longitudinally 75 through said casing which valve member in one position puts the supply pipe in communication with the inflow pipe and the outflow pipe in communication with the discharge pipe and in another position shuts off the inflow and outflow pipes and puts the supply pipe in direct communication with the discharge pipe, a piston connected with said valve member, a cylinder in which said piston operates, and means for supplying 80 fluid under pressure to the cylinder from said supply pipe.

9. In a heating system, the combination 85 of a supply pipe, a radiator having inflow and outflow pipes, a discharge pipe, and a controlling device comprising a casing having 90 ports communicating with said pipes, a valve member movable longitudinally through said casing which valve member in one position puts the supply pipe in communication with the inflow pipe and the outflow pipe in communication with the discharge pipe and in an alternative position shuts off the inflow and outflow pipes and puts the supply pipe in direct communication 95 with the discharge pipe, said valve member being revoluble and adapted to effect the alternative connections above specified by angular movement as well as by longitudinal movement, a piston connected with said valve member, and a cylinder in which said piston operates which is adapted to receive pressure fluid.

10. In a heating system, the combination 100 of a supply pipe, a radiator having inflow and outflow pipes, a discharge pipe, and a controlling device comprising a casing having ports communicating with said pipes, a valve member movable longitudinally 105 through said casing which valve member in one position puts the supply pipe in communication with the inflow pipe and the outflow pipe in communication with the discharge pipe and in an alternative position shuts off the inflow and outflow pipes and puts the supply pipe in direct communication 110 with the discharge pipe, said valve member being revoluble and adapted to effect the alternative connections above specified by angular movement as well as by longitudinal movement, a piston connected with said valve member, a fluid pressure cylinder in which said piston operates, and a spring which tends to move said valve member in the direction opposite to the 115 120 125

movement imparted thereto by the piston when under pressure.

11. In a heating system, the combination of a supply pipe, a radiator having inflow and outflow pipes, a discharge pipe and a controlling device comprising a casing having ports communicating with said pipes, a valve member movable longitudinally through said casing which valve member in one position puts the supply pipe in communication with the inflow pipe and the outflow pipe in communication with the discharge pipe and in another position shuts off the inflow and outflow pipes and puts the supply pipe in direct communication with the discharge pipe, a piston connected with said valve member, a fluid pressure cylinder in which said piston operates, and a valve for governing the inflow of pressure fluid to the cylinder.

12. In a heating system, the combination of a radiator, a supply pipe and a valve member which may be moved either longitudinally or revolubly to admit heating medium from the supply pipe to the radiator or close communication between said pipe and said radiator.

13. In a heating system, the combination of a radiator, a supply pipe, a valve member which may be moved either longitudinally or revolubly to admit heating medium from the supply pipe to the radiator or close communication between said pipe and said radiator, a handle for effecting one of said movements manually, and other motive means for effecting the other of said movements.

14. In a heating system, the combination of a radiator, a supply pipe, a valve member which may be moved either longitudinally or revolubly to admit heating medium from the supply pipe to the radiator or close communication between said pipe and said radiator, a handle for revolving the valve member, and other motive means for moving the valve member longitudinally.

15. In a heating system, the combination of a radiator, a supply pipe, a valve member which may be moved either longitudinally or revolubly to admit heating medium from the supply pipe to the radiator or close communication between said pipe and said radiator, a handle for revolving said valve member, a fluid pressure motor for imparting longitudinal movement to the valve member in one direction, and a spring for moving it in the opposite direction.

16. In a heating system, the combination of a radiator, a supply pipe, a valve member which may be moved either longitudinally or revolubly to admit heating medium from the supply pipe to the radiator or close communication between said pipe and said radiator, a handle for revolving said valve member, a fluid pressure motor for

imparting longitudinal movement to the valve member in one direction, a spring for moving it in the opposite direction, and a valve for governing the admission of pressure fluid to said motor.

17. In a heating system, the combination of a supply pipe, a radiator having inflow and outflow pipes, a discharge pipe, a controlling device comprising a casing having ports communicating with said pipes and a drain port, a valve member movable longitudinally through said casing and revolubly therein, formed with two longitudinally extending webs arranged successively lengthwise of the member and standing at an angle with respect to each other, one of said webs in one longitudinal position of the valve being so arranged as to put the supply pipe in communication with the inflow pipe, and the outflow pipe in communication with the discharge pipe and close said drain port, the other of said webs being so arranged as to shut off the inflow and outflow pipes, open the drain port and put the supply pipe in communication with the discharge pipe, a piston on one end of said valve member, a cylinder in which said piston operates, a spring adapted to bear against the other end of said valve member, a revoluble member provided with a handle and having a slideable non-rotatable engagement with said valve member, and means for admitting pressure fluid to said cylinder.

18. In a heating system, the combination of a supply pipe, a radiator having inflow and outflow pipes, a discharge pipe, a four-way valve having ports communicating with said pipes, and a drain port, said valve being provided with a revolubly and longitudinally movable valve member comprising two webs arranged successively lengthwise of the member at right angles to each other, a handle for revolving said valve member, a piston on one end of said valve member, a cylinder in which said piston operates, a spring bearing against the other end of said valve member, a valve chamber adjacent said cylinder and communicating therewith provided with an inlet port and an exhaust port, a pressure fluid supply pipe leading to said inlet port, a double valve in said valve chamber arranged to close said ports alternately, a spring to move said valve in one direction, a rock arm bearing against the valve to move it in the other direction, and means for giving angular movement to said rock arm.

19. In a heating system, the combination of a radiator having inflow and outflow pipes, a four-way valve comprising a casing divided so as to have four chambers with two of which said pipes communicate, and a revolubly mounted and longitudinally movable valve member which is arranged in said casing and is formed with a pair of webs one beyond the other lengthwise of the

valve which stand at an angle to each other, means for imparting longitudinal movement to said valve member, and a handle for revolving said valve member manually.

5 20. In a heating system, the combination of a radiator, a supply pipe, a valve member which may be moved either longitudinally or revolubly to admit heating medium from the supply pipe to the radiator or close

communication between said pipe and radiator, means for moving the valve longitudinally, and means for rotating the valve member comprising a revoluble member provided with a handle and having a sliding non-rotatable engagement with said valve member.

EDWARD A. RUSSELL.
